JASPER B. WILLSEA, OF ROCHESTER, NEW YORK, ASSIGNOR TO WILLSEA WORKS, OF ROCHESTER, NEW YORK, A CORPORATION OF NEW YORK

CLIP FOR SHEET MATERIAL

Application filed April 5, 1929. Serial No. 352,752.

The invention relates to clips for holding or suspending sheets of paper or like material, and especially to that form of clip in which a pivoted dog swings between the arms of an inverted U-shaped member and engages the sheets between itself and one of the arms of said member.

The object of the invention is to provide a clip of this kind with a dog having its 10 engaging surface formed on a curve of long radius with means for stopping the movement of the dog before it fully engages the gripping surface.

A further object of the invention is to 15 provide a clip of this kind with a dog having its engaging surface formed on the curve of an Archimedes spiral with a stop adapted to engage the gripping surface before the dog makes locking contact therewith.

Another object of the invention is to 20 provide a dog of this kind with a stop adapted to engage the gripping member when there is no material in the clip but which is free from sheets in the clip.

To these and other ends the invention consists in the construction and arrangement of parts that will appear from the following description when read in conjunction with the 25 accompanying drawings, the novel features 30 being pointed out in the claims following the description.

In the drawings:

Figure 1 is a side elevation of a clip constructed according to one embodiment of the 35 invention;

Figure 2 is a front elevation of the same;

Figure 3 is a side elevation of the clip showing a plurality of sheets held therein, and

Figure 4 is a side elevation showing the 40 dog in releasing position.

Similar reference numerals refer to the same parts in all the figures of the drawings.

The form of the invention illustrated in the accompanying drawings comprises a 45 body member 1 of inverted U-shape having downwardly extending and slightly divergent arms 2 and 3, and a circular opening adjacent its upper end by means of which it may be adjustably mounted on a rod or shaft 4. A set screw 5 is threaded therein

and adapted to engage the supporting rod to hold the clip against movement thereon.

The arm 3 is provided with a longitudinally extending slot in the lower end of which is mounted a dog or clamping member 6. The dog 6 is pivoted at 7 and normally extends laterally downwardly and upwardly and engages the arm 2 or one or more sheets 8 gripped between the dog and the arm 2. The outer engaging or gripping surface 9 of the dog is curvilinear in form and preferably of a curve having a long radius of curvature, such as a spiral of Archimedes, to provide as large a surface as possible to contact with the sheets held in the clip. The dog 6 swings freely on its pivot under the force of gravity, normally assuming the positions shown in Figures 1 and 3 in contact with the arm 2 or sheets gripped between it and said arm. If desired the dog may have its lower inner portion enlarged or thickened, as at 10, to increase its weight and consequently the force with which it engages or clamps the sheets.

These clips are frequently employed for 75 suspending sheets of damp or wet paper in drying apparatus, in which condition the sheets are very susceptible to injury. The sheets are suspended from a pair of the clips and the operator inserts them from below, 80 raising the dogs by means of the sheets.

When the surface of the dog is in the form of an Archimedes spiral generated about the pivot of the dog, it enables the clip to hold varying thicknesses of sheet material with 85 practically the same clamping action, regardless of the thickness of sheet material inserted. This is brought about by the fact that such a curve in any position presents a large diameter arc.

When the clip is empty, the wedging action of the two surfaces when produced only by the weight of the dog itself makes necessary considerable force to release it, and when inserting sheets into a pair of such clips, holding the sheets with both hands, it is desirable to open the clips by pushing the dogs up with the material itself as both hands are occupied in holding the paper. The wedging of the dog makes it impossible to exert enough 90 95 100

pressure to open it without damaging or mutilating the sheets, unless some means is provided to prevent such wedging action.

I have provided means for preventing the gripping surface of the dog from falling into contact with the arm 2 and wedging thereagainst when no paper is in the clip. In the present instance said means comprises a stop, short lug or projection 11 on the dog 6, preferably at the upper end of the curved surface 9, adapted to engage the clamping arm 2 just before the gripping surface on the dog engages the arm. By this arrangement, the dog is always free to move, and the inserted sheets can readily raise the dog and are passed between the gripping surfaces without injury.

While the invention has been described with reference to a particular embodiment, it is not limited to the specific disclosure shown, and this application is intended to cover such changes or modifications as come within the intent of the improvement of the scope of the following claims.

25 I claim:

1. A clip for sheet material comprising a body member having a pair of spaced arms, a dog having a clamping portion pivoted to the end of one of said arms and movable by gravity to clamp one or more sheets between it and the other arm, and a stop adjacent to said clamping portion for engagement with said other arm to arrest the movement of the dog before its clamping portion engages said other arm so that the dog may yield more easily to permit one or more sheets to be inserted when engaged thereby.

2. A clip for sheet material comprising a body member having a pair of spaced arms, 40 one of said arms having a slot, a dog having a clamping portion pivoted in the end of said slot and movable to clamp one or more sheets between it and the other arm, and a stop arranged on the dog opposite its pivot and adapted to engage said arm before its clamping portion engages therewith so that the dog may yield more easily to permit one or more sheets to be inserted when engaged thereby.

50 3. A clip for sheet material comprising a body member having a pair of spaced arms, a dog pivoted to one of said arms movable by gravity to clamp one or more sheets between it and the other arm, said dog having a curved engaging surface formed on a curve of long radius, and a stop for arresting the movement of the dog before its curved engaging surface contacts with said other arm so that the dog may be freely moved by an 55 engaging sheet.

60 4. A clip for sheet material comprising an inverted U-shaped body member, one of the arms of said body member being slotted, a dog pivoted in the lower end of said slot and movable to clamp one or more sheets between

it and the other arm, said dog having a weighted portion to move it to clamping position, and a curved engaging surface formed on a curve of long radius to present a large clamping area to the sheets in all clamping positions, and a stop at the upper end of said curved surface to prevent wedging of the dog between the arms.

5. A clip for sheet material comprising a body member having a pair of divergent depending arms, a dog pivotally mounted on one of said arms and movable into clamping engagement with the other of said arms, a weight on said dog tending to move it into clamping engagement with said arm and adapted to limit its movement away from said arm, and a stop on the dog adapted to engage said arm for arresting the movement of the dog before it engages the arm.

In witness whereof, I have hereunto signed my name.

JASPER B. WILLSEA.
